STOCKING FORM

Charles S. Tiers, Philadelphia, Pa., assignor to
 Proctor & Schwartz, Inc., Philadelphia, Pa., a
 corporation of Pennsylvania

Application January 24, 1951, Serial No. 207,503

2 Claims. (Cl. 223—75)

1.

This invention relates to new and useful improvements in stocking forms of the type on which full-fashioned hosiery customarily is mounted for drying, setting and other finishing treatments.

It has been customary for many years in the hosiery industry to utilize stocking forms which are constructed to locate the stocking seam substantially at the back of the stocking, for example, by providing an inwardly offset recess or groove at one side of the stocking form which extends along the rear and bottom edges of the form continuously throughout the leg and foot portions thereof, so that the seam of the stocking is disposed in one side of the stocking and not precisely along the rear crease or fold line thereof.

Disposing the stocking seam in this manner at one side of the rear crease or fold therein is desirable in the leg portion of the stocking. This is so because the seam is relatively bulky and it is substantially impossible to position the seam exactly on the rear crease or fold line of the stocking through the entire length thereof, the seam tending to shift laterally onto one or both sides of the form in different portions of the length thus creating an appearance which is lacking in uniformity. Furthermore, there is no contrasting or other structural or design element of the stocking adjacent the leg seam portion with respect to which it is desirable to position the seam.

However, this is not true in the case of the foot and heel portions of the stocking where the adjacent leg and reinforced heel and foot portions provide contiguous areas of contrasting colors or designs at opposite sides of the stocking which it is desirable to dispose in accurate overlying registry when the stocking is removed from the form and folded flat in a box, envelope or other container in which it is displayed and sold.

In the case of stocking forms having the customary seam recess at one side of the form as previously described the seam in the heel and foot portions of the stocking is disposed in one side of the stocking the same as it is in the leg portion previously described. This offset of the seam in the heel and foot portions into one side of the stocking effects a corresponding offsetting of the contrasting color areas and designs in opposite sides of the stocking so that these areas and designs are not in overlying registry and create a confusing undesirable effect upon the customer. This is particularly true in the case of stockings embodying so-called framed heel

2.

and similar designs since such lack of registry of the designs at opposite sides of the stocking makes it extremely difficult for a customer to observe and determine the exact design of the stocking.

With the foregoing in mind, the principal object of the present invention is to provide a stocking form of the type set forth which embodies novel features of construction and arrangement operable to insure substantial overlying registry of the contrasting areas and designs in opposite sides of the stocking at the juncture of the leg portion and reinforced heel and foot portions of the stocking when the stockings are removed from the form and folded flat.

Another object of the invention is to provide a novel stocking form which embodies the construction and arrangement set forth in combination with structure operable to dispose the seam in the leg portion of the stocking in one side of the stocking with respect to the rear crease or fold therein.

These and other objects of the invention and the various features and details of the construction and operation thereof are hereinafter fully set forth and described with reference to the accompanying drawing, in which:

Fig. 1 is a side elevational view of a stocking form made according to the present invention;

Fig. 2 is an enlarged sectional view on line 2—2, Fig. 1;

Fig. 3 is an enlarged sectional view on line 3—3, Fig. 1;

Fig. 4 is an enlarged fragmentary perspective view of a section of the rear edge portion of the stocking form which is embraced by the bracket in Fig. 1;

Fig. 5 is a perspective view of a stocking removed from a form of the present invention and folded flat with the contrasting areas and design at the juncture of the leg and reinforced heel and foot portions at opposite sides of the stocking disposed in overlying registry; and

Fig. 6 is an elevational view of the foot portion of a stocking showing the contrasting areas and designs in one side of the stocking offset and out of register with respect to the similar areas and designs at the other side of the stocking.

Referring now more particularly to the drawing, reference numeral 1 designates a stocking form made according to the present invention. The form may be made of metal or other suitable material and preferably is of solid relatively thin construction and substantially flat as shown in Figs. 2 and 3 of the drawing. The front edge 2

of the stocking form may be beveled on both sides as indicated at 3 in Figs. 2 and 3.

In accordance with the present invention the stocking form is provided at its rear edge with a recess or groove at one side of the form to receive the seam of the leg portion of the stocking and is provided with a centrally edgewise recess or groove in the heel and foot portions of the form to receive the seam of the heel and foot portions of the stocking.

Thus at one side of the stocking form, there may be provided adjacent the rear of the stocking form 1, at one side of the latter, a leg seam portion recess 4 which may be defined by an inwardly offset flat marginal portion 5 that extends inwardly from the form rear edge substantially parallel to the form side walls and terminates at its inner edge in an outwardly and forwardly beveled surface portion 6, for example, as shown in Fig. 2 of the drawing.

The surfaces 5 and 6 preferably extend continuously from the upper end of the form downwardly along the rear edge thereof to a point which is located at or a short distance above the junction of the leg portion of the stocking and the top of the reinforced heel portion thereof, for example, as indicated at 7 in Fig. 1.

Commencing at the point 7 there is provided in the rear edge of the stocking form 1 an inwardly recessed groove 8 for receiving the stocking seam. The groove 8 extends continuously from the point 7 downwardly along the rear heel portion of the form 1 and thence along the bottom edge of the foot portion to the toe of the form 1 where it terminates as shown. The recess or groove may be V-shape in cross-section as shown, or otherwise as desired.

It is important to note that the groove or recess 8 is disposed edgewise of the stocking form centrally between and with respect to the opposite side faces of the form, for example, as shown in Fig. 3 of the drawing. By this arrangement the stocking seam in the heel and foot portions of the stocking is disposed in the rear crease or fold of the stocking instead of in one side of the stocking as in the case of the leg seam portion which is received and positioned by the recess 4 defined by the surfaces 5 and 6 of the form leg portion. To maintain controlled positioning of the stocking seam throughout its length at all times, the lower end of the leg seam recess 4 and the upper end of the heel and foot seam groove 8 are made to intercommunicate, for example, as shown in Fig. 4 of the drawing.

By this construction it will be apparent that

the seam in the heel and foot portions of the stocking is advantageously positioned centrally along the rear and bottom edges of the form 1 while the seam in the leg portion of the stocking is disposed in one side of the stocking and not precisely on the rear fold or crease line thereof as desired. Thus a stocking which is dried, set or otherwise finished upon a form constructed according to the present invention will have the heel and foot portion of its seam disposed in the fold or crease of the stocking so that when the stocking is removed from the form and laid flat the contracting areas and design at the juncture of the leg portion and reinforced heel and foot portions at opposite sides of the stocking will be disposed in overlying registry with each other as indicated in Fig. 5 of the drawing, as distinguished from an offsetting of such areas and designs relative to each other, for example, as illustrated in Fig. 6, wherein such areas and designs are out of register.

While a particular embodiment of the invention has been illustrated and described herein it is not intended that the invention be limited to such disclosure and changes and modifications may be made within the scope of the following claims.

I claim:

1. A stocking form having generally flat sides and comprising leg, heel and foot portions, the leg portion of the form having an inwardly offset recess in one side of the form extending adjacent the rear edge thereof from the top of the leg portion continuously to a point adjacent the top of the heel portion of the form, and the heel and foot portions of the form having a V-shape groove in the rear and bottom edges respectively thereof disposed centrally between the opposite flat sides of the form and extending from the lower end of said recess continuously along the rear heel portion and bottom edge of the foot portion to the toe of the form.

2. A stocking form as claimed in claim 1 wherein the lower end of the leg recess interconnects with the upper end of the groove in the heel and foot portions of the form.

CHARLES S. TIERS.
